US0D1051645S

(12) **United States Design Patent** (10) **Patent No.:** **US D1,051,645 S**
(45) **Date of Patent:** **** Nov. 19, 2024**

(54) **SHELF**

(71) Applicant: **Na Wei**, Jieyang (CN)

(72) Inventor: **Na Wei**, Jieyang (CN)

(**) Term: **15 Years**

(21) Appl. No.: **29/943,453**

(22) Filed: **May 22, 2024**

(51) LOC (14) Cl. **06-04**

(52) U.S. Cl.

USPC **D6/676.1**

(58) **Field of Classification Search**

(57) **CLAIM**

The ornamental design for a shelf, as shown and described.

DESCRIPTION

FIG. 1 is a front, right, top perspective view of the shelf, showing my new design;

FIG. 2 is a rear, left, bottom perspective view thereof;

FIG. 3 is a front, left, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The dashed broken lines in the figures are for the purposes of illustrating portions of the shelf and form no part of the claimed design.

1 Claim, 9 Drawing Sheets
